UNITED STATES PATENT OFFICE.

STEPHEN A. D. HARTMAN, OF CHARLES CITY, IOWA.

HARROW.

SPECIFICATION forming part of Letters Patent No. 339,408, dated April 6, 1886.

Application filed July 2, 1885. Serial No. 170,503. (No model.)

To all whom it may concern:

Be it known that I, STEPHEN A. D. HARTMAN, a citizen of the United States of America, residing at Charles City, in the county of 5 Floyd and State of Iowa, have invented certain new and useful Improvements in Harrows; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 My invention relates to wheel or sulky harrows; and it consists in the improvements hereinafter described and set forth.

In the accompanying drawings, which illustrate my invention, Figure 1 is a plan view of 20 my improvement. Fig. 2 is a front view showing each of the sections raised, and Fig. 3 is a side view.

A represents the main or carrying frame, which converges from the rear supporting-wheels, A', which are mounted on an axle, a, 25 the side beams of the frame converging toward each other to a point in front of the harrow-section.

At the front of the main frame A is located 30 a caster-wheel, B.

C represents the central section of the harrow, which consists of longitudinal diverging beams c c c', which are connected to each other by transverse beams d d' d''. Beams e are also 35 attached to the front end of this central harrow-section, and converge rearwardly toward each other, thus providing at the front portion of this harrow-section a space in which the caster-wheel B may play.

40 To the side beams, c c, of the central harrow-section, C, are attached outwardly-projecting bars f f, the ends of which are provided with eyes. By having the beams c c diverge rearwardly from the front of the harrow-section, 45 a space is provided for the supporting-wheels A', and the front portions of the side sections or wings, D, swing rearwardly when said side sections are elevated, so as not to interfere with the horses. The side sections, D D, are provided with longitudinal beams, which are par-

allel with the side beams, c c, of the central section, and said beams are connected to each other by transverse strips, in the usual manner. These side sections are also provided with hooked bars f', which engage with the bars f 55 on the central section.

The carrying-frame A is provided near its rear portion with a driver's seat, E, and in front of said seat, so as to be within easy access of the driver, are located three upright bars, h h, adjacent to which are located rack-bars i, which are adapted to engage with cam-levers I, which are attached or pivoted to a transverse bar, k. The central lever is for the purpose of elevating the central harrow-section, and a flexible connection extends from the same and is attached to the transverse bar d'. Immediately in the rear of this cross-bar d' the harrow-section C is provided with an upwardly-projecting bar, L, which is attached 70 to the cross-bar d, and passes through a perforation, l, in the carrying-frame A. This upright bar serves as a guide for the central harrow-section in raising and elevating the same. Flexible connections m are attached 75 to the side levers, and pass from thence under pulleys m', which are swiveled to the edges of the carrying-frame, after which the cords or chains are carried slightly forward and attached to the side wings, D, as shown. It 80 will be evident that when the levers are depressed the sections will be raised, and when raised will assume the position shown in Fig. 2 of the accompanying drawings.

To the forward portion of the main frame 85 A, adjacent to the caster-wheel B, are secured two curved bars, o o, which are pivotally connected to the end of the main frame and rest upon a transverse pin, o', which projects on each side of the end of the main frame. These 90 bars, after being curved downwardly, are bent so as to form eyes, which engage with the eye of the king-bolt p, which connects the single-tree O and the draft-tongue O' with each other. The ends of the single-tree or draft-bar are 95 connected to the ends of each of the harrow-sections by chains q, which are attached to the corners of the central harrow-section and to the side sections, as shown. The draft-tongue O' is rigidly connected to the single-tree by 100

means of bars *r*, which are pivotally connected to the single-tree and are hooked into projections *s*, attached to the side of the tongue.

I claim—

- 5 The combination, with a main frame or carriage supported at its front by a caster, of a harrow-section located beneath said main frame or carriage, and provided at its front with converging bars *e e*, and devices for rais-

ing and lowering said harrow-section, substantially as set forth.

In testimony whereof I affix my signature in presence of two witnesses.

STEPHEN A. D. HARTMAN.

Witnesses:

DANIEL F. HARTMAN,
HERRMAN KRUGER.
